DIVING UNIT

Hugh D. Wilson, Goleta, Calif., assignor to Union Carbide Corporation, a corporation of New York

Filed Apr. 1, 1964, Ser. No. 79,303

Term of patent 3½ years

(Cl. D71—1)

FIG. 1 is a perspective view of a diving unit, showing my new design;

FIG. 2 is a side elevational view thereof; and

FIG. 3 is a top plan view thereof.

I claim:

The ornamental design for a diving unit, as shown.
